(57) **CLAIM**

The ornamental design for a sport bar, as shown and described.

DESCRIPTION

FIG. 1 is a perspective view of a sport bar according to the new design;

FIG. 2 is a front view of the sport bar seen in FIG. 1; FIG. 3 is a back view of the sport bar seen in FIG. 1; FIG. 4 is a left side view of the sport bar seen in FIG. 1; FIG. 5 is a right side view of the sport bar seen in FIG. 1; FIG. 6 is a top view of the sport bar seen in FIG. 1; and, FIG. 7 is a bottom side view of the sport bar seen in FIG. 1. In the drawings, the broken lines depict environmental subject matter only and form no part of the claimed design. Shade lines having a combination of long and short lines in the drawings show contour and not surface ornamentation.
